UNITED STATES PATENT OFFICE.

HAROLD CARLE, OF BUFFALO, NEW YORK, ASSIGNOR TO F. N. BURT COMPANY, LIMITED, OF BUFFALO, NEW YORK, A CORPORATION OF ONTARIO, CANADA.

LABELING-MACHINE.

1,180,006.

Specification of Letters Patent. Patented Apr. 18, 1916.

Application filed May 5, 1914. Serial No. 836,400.

To all whom it may concern:

Be it known that I, HAROLD CARLE, a subject of the King of Great Britain, citizen of Canada, residing at Buffalo, in the county of Erie and State of New York, have invented certain new and useful Improvements in Labeling-Machines, of which the following is a full, clear, and exact description, such as will enable others skilled in the art to which it appertains to make and use the same.

This invention relates to machines for applying labels or strips to articles such as paper boxes, and with respect to its more specific features, to devices of the character referred to for automatically applying a label or strip of paper, cloth, etc., across the joint and on two sides adjacent the jointed side of a sectional box.

One of the objects of the invention is to provide a machine of the character referred to which shall be simple in construction and efficient in operation.

Another object of the invention is the provision of a practical device of the character described which shall be compact and take up but little floor space.

Still another object of the invention is the provision of a practical mechanism wherewith the label or strip may be securely adhesively attached on the jointed face of a sectional box, and also the provision of a practical device for applying adhesive in a uniform coat.

In the accompanying drawings, wherein similar reference characters refer to similar parts throughout the several views, Figure 1 represents a right side elevation of a machine embodying this invention; Fig. 2 is a plan view of the same; Fig. 3 is a vertical longitudinal section taken on the line 3-3 of Fig. 2; Fig. 4 is a vertical transverse section taken substantially on the line 4-4 of Fig. 2; Fig. 5 is a view looking in left side elevation at the machine, showing the vertical box feed and safety stop control mechanism; Fig. 6 is an enlarged longitudinal central sectional detail, taken through a set of adhesive-applying members; Fig. 7 is a longitudinal central section taken through a set of the adhesive-applying members when the same is in box feeding position; Fig. 8 is a sectional view similar to Figs. 6 and 7 except that a box is being fed relative to the members and assembled with a label; Fig.

9 is a plan view of the mechanism for discharging the labeled boxes from the machine; Fig. 10 is a right side elevation of the mechanism shown in Fig. 9; Fig. 11 is a plan view of the end of the box guide or trough arranged below the vertical box feed; Fig. 12 is a view in right side elevation of the mechanism for applying adhesive to the pads or sets of adhesive-applying members; Fig. 13 is a view in right side elevation of the label magazine and actuating mechanism therefor; Fig. 14 is a view of the mechanism for actuating the relatively movable member of the adhesive-applying member; Fig. 15 is a view of the label press, or padder, and actuating mechanism; Fig. 16 is a view of the mechanism for folding and smoothing the label on the boxes; Fig. 17 is a view of the guiding means for the boxes in the lower channel, showing the box press; Fig. 18 is a view of the box magazine, or primary feed for the boxes; and Fig. 19 is a sectional view taken on the line 16-16, Fig. 2. Fig. 20 is a perspective view showing a box to which a label is applied.

The invention accordingly consists in the features of construction, combinations of elements and arrangement of parts which will be exemplified in the construction hereinafter set forth, and the scope of the application of which will be indicated in the following claims.

Referring now more specifically to the drawings, the numeral 1 represents a supporting frame or horizontal table having suitable legs 2. On the top of the table, near one end thereof, are standard bearings 3 supporting the horizontal main driving shaft 4, on which latter is rotatably mounted the belt pulley 5, and the shaft 4 is adapted to be coupled to the pulley 5 by means of a clutch 6 of any suitable type, preferably a friction clutch. A hand-wheel 7 is secured to the shaft 4 for the manual operation thereof when desired. The operation of the various elements of the machine is effected from the driving shaft 4. Supported in brackets 8 fastened to the under surface of the table is a main cam shaft 9 horizontally arranged and from which, through the instrumentality of proper cams, many of the different motions of the several operating parts of the machine are effected. The cam shaft 9 is continuously driven, having a sprocket wheel 10 fixed thereto engaged by

sprocket chain 11, with which also engages a sprocket wheel 12 on a horizontally arranged countershaft 13 supported in standards 15 on the upper surface of the table, the countershaft having a relatively large pinion 16 meshing with a small gear 17 fixed to the main driving shaft 4.

At the intermediate portion of the table are mounted two standards 18 and 19 in which is journaled a horizontal shaft 20 bearing at one end supporting, or carrier, arms 21, vertically disposed. The arms 21 are of equal length and to the outer end of each arm is fastened a set of adhesive applying members mounted to move in a vertical plane. In the present embodiment each set comprises a flat metallic plate 22 disposed in a plane normally to the vertical plane and having an intermediate opening 23, said plate being made in sections fastened together, if preferred. At each side of the opening 23 the plates 22 are provided with pads 24 of a character adapted to receive a coating of adhesive and to give the adhesive means of transfer it to labels or strips which may be applied on the surface of the pads 24. These pads are flush with the edges of the opening 23 and are of such a length and width as to comport with the part of the label the adhesive is to be applied to, as will hereinafter appear. Each set of adhesive-applying members preferably comprises a flat plate 25 having a pad 26 of the same character as the pads 24, and the plate 25 is mounted to move into and out of the opening 23. When the plate 25 is in the opening, the pad 26 is flush with the pads 24, and the size thereof compared with the size of the opening 23 is such that when in said opening the pads 24 and 26 provide a practically continuous flat surface for the reception of adhesive and for the support of a label which may be applied thereto. In the present embodiment there are four sets of the adhesive-applying members, and it will be understood that the sets of adhesive-applying members are of similar structure and arrangement and comprise similar operating devices, and hence a description of the details of one set will suffice for all. In order to effect the movements of the plate 25 into and out of the opening 23, the same is supported by an arm 27 fixed to the pivot 28 journaled in the supporting member 21, a pinion 29 being fixed to the pivot 28 and meshing with teeth 30 of one arm of a lever 31 fulcrumed on the supporting arm 21, the other arm leaving a pin and slot connection with a slideable squared rod 32 guided in a bracket 33 on the member 21. A stop or shoulder 27 limits the inward movement of the central pad. It is designed to dispose the pad 26 both with the pads 24 at certain times and at certain other times to remove said pad

from the opening 23 in order that a box or other article may be passed into and through said opening and into contact with a label or strip spanning said opening and adhesively supported by the pads 24. Four sets of adhesive-applying members are provided, and there are, therefore, four movable pads 26. The sets of adhesive-applying members are intermittently moved in an endless path and preferably in a vertical plane, as by being rotated in a vertical plane through the instrumentality of the shaft 20 as will presently appear, and labeling operations are performed at or adjacent the different points of rest in the path of said sets. 70 As will hereinafter appear, adhesive is applied to the sets while approaching one of the positions of rest, preferably as the sets are just assuming a vertical plane, labels are applied thereto at a succeeding and horizontal position, the label is pressed and smoothed on the members at another, preferably vertical, position of rest, and immediately thereafter the pad 26 is moved away from the label, leaving the latter adhesively supported on the pads 24 and also leaving a free passageway through the opening 23 from the inside of the path of the adhesive-applying members and toward the label by the time the members assume their next position of rest, which is preferably horizontal. 80

After the pad 26 is moved away from the label, the article or box to be assembled with the label is moved into contact therewith at the next succeeding position of rest of the members, and in order to effect this removal of the pad 26, the rod 32 is positively moved in a proper direction to accomplish the same. This motion of the rod is effected through the instrumentality of a cam guide 34 pivotally connected to one end of a link 35 having its other end pivoted on the table 1, said guide 34 having a slot 36 through which the countershaft 13 passes and assists in supporting the same and being slightly hollowed, as shown at 39', to obtain more direct thrust on roller 39. Adjacent the guide 34 the countershaft 13 is provided with a cam 37 which co-operates 100 with the anti-friction roller 38 on cam guide 34 and effects the positive movement of the guide 34 in a direction to contact the rod 32, preferably through the instrumentality of an anti-friction roller 39 on the rod, a 105 spring 40 being employed to retract the cam guide 34 and to retain the roller 38 in contact with the cam 37. The pad 26 is moved into position flush with the pads 24 preferably by means of a coil spring 41 surrounding the pivot 28, one end of said spring having proper engagement with said pivot so as to turn the same, and the other end of said spring being fixed to the supporting member 21. The numeral 42 indi- 110

cates a fixed retaining member or concentric cam track supported by standard 18, which track is engaged by the roller 39 as the supporting member 21 rotates and after 5 the cam guide 34 has effected the described positive movement of the rod 32 so as to cause said roller 39 to roll off the guide 34 onto said track. The initial engagement of the track 42 by the roller 39 is effected before 10 the adhesive-applying members reach their lowermost position, or position where the boxes are assembled with the labels, and one of the main utilities of said track or cam is to positively prevent the pads 26 from being restored to flush position during 15 the assembly of the box with the label. But just before the adhesive-applying members reach their position adjacent the mechanism which supplies adhesive, as glue, thereto, the roller 39 rolls off the farther end of cam track 42 and thereupon the spring 41 restores the pad 26 to position flush with the pads 24, and yieldingly holds the same in such flush position while glue is being applied thereto, while a label is being applied to the glued surface thereof and while an adhering label is pressed or patted against said glued surface. The end portion of the track 42 has a less degree of curvature than 25 the concentric portion, as seen at 42', so as to permit the pad 26 to close gradually rather than with a snap.

43 indicates an adhesive supply tank supported on an elevated framework 44 supported on the table 1 and adjacent one of the vertical positions of rest of the adhesive-applying members.

45 represents an adhesive supply roller dipping into the supply of adhesive or glue 30 in the tank, and 46 represents an adhesive-applying roller journaled in a yoke 47 pivoted on the framework 44 and having an arm 48 to which is connected a rod 49 having a slot 50 engaging the cam shaft 9. The 35 roller 46 is normally outside of the rotary path of the adhesive-applying members. Adjacent rod 49 the shaft 9 carries a cam 51 the surface of which is adapted to engage an anti-friction roller 52 on the end of rod 49, and a spring 53 is attached to another arm 54 of the yoke 47 and to the framework 44 and is adapted to move roller 46 toward the adhesive-applying members. It will be observed that the adhesive-applying members 40 are flat on their active surfaces, and, in order that a coat of adhesive of substantially equal depth throughout, or a uniform coat, may be applied to these flat surfaces, the cam 51 is so shaped as to permit the roller 46 to move from the roller 45 to or toward said flat surface, and to control or govern the path of movement of the roller 46 so that it shall exert a uniform pressure throughout said flat surface notwithstanding the fact 45 that different parts of this surface are at different distances from the center of motion. It will be understood that the roller 46 applies adhesive to the pads 24 and 26 when the latter is in flush position. The roller 46 is moved into adhesive-applying 50 position after the members to which the adhesive is to be applied come to rest adjacent thereto, and said roller rolls on the members, transfers adhesive thereto, and rolls off said members as said members move to their next 55 position of rest adjacent the label magazine. Thereafter the adhesive coated members move to their upper position of rest where they are adjacent the label supply. This latter comprises a head 54' supporting a label magazine, also normally outside of the path of the adhesive-applying members, and comprising flexible arms 55 attached to a plate 53' adjustably fastened to the head 54' and spaced apart to receive a pack of labels 60 or cover strips. The pack lies within the arms 55 and is adapted to gravitate toward the bottom of the receptacle so formed, the bottom label being held by fine points at the ends of the arms 55. When the adhesive 65 coated members are in their uppermost position of rest, the pack is brought down thereagainst by means of a cam 56 on the shaft 9 and a coöperating lever 57 and link 58, the latter being connected to a supporting and guiding rod 59 secured to the head 54'. 60 is an additional guide rod for the head. As the labels lie in the magazine the bottom of the pack slightly bulges downwardly so that there is no difficulty in effecting contact between the bottom label and the adhesive coated surface of the members. The cam 56 is so shaped as to effect such contact and thereafter raise the pack, the bottom label of the pack adhering to and being retained on said members. The specific construction of this label holder is not claimed herein, but it may be noted that the arms 55 may be adjusted to accommodate labels of different sizes, and that these arms 70 are carried by a plate 53', which is adjustable laterally on the head 54' so as to permit the label holder to be accurately set in proper position. The specific construction of the label magazine and appurtenant parts is similar to that disclosed in the application of R. Burt, filed July 10, 1913, Serial No. 778,255. The members are next moved to a succeeding vertical position opposite a combined presser and smoother 61, which comprises a plate having a pad surface 62 and mounted upon one arm of a lever 63 fulcrumed at 64 on the table. To the other arm of the lever 63 is connected a rod 65 having an anti-friction roller 66 and a slot 67 engaging the cam shaft. On the cam shaft adjacent the rod 65 is a cam 68 adapted to contact roller 66, and which is shaped and timed to positively cause the pad 62 to press the adhering label against the pads 75 80 85 90 95 100 105 110 115 120 125 130

24 and 26 in the position of rest referred to, spring 69 connecting the rod 65 and the main frame and serving to move the presser 61 away from the adhering label, the cam permitting. It may here be noted that the cam 37 causes the pad 26 to move away from the label before the pressure of the presser 61 is relieved, and in this manner displacement of the label from accurate position is prevented.

10 The connection between the lever 63 and rod 65 is such as to be adjustable to permit the machine to be run idly without the presser 61 contacting with the gluing pads.

15 By withdrawing the pin 65' from one of the slots 66', and moving lever 63 so as to cause said pin 65' to engage the other slot 66', the presser 61 will not contact the glue pads as the machine operates (see Fig. 15). There-

20 after the members are moved into their lowermost position, but prior to assuming such latter position the intermediate pads 26 are moved out of the opening 23, as before described.

25 The articles to be assembled with the labels are preferably rectangular boxes comprising a base and a cover which, when assembled, present flush surfaces on the jointed faces, an example of such a box be-

30 ing the well-known cigarette box, as shown in Fig. 20. These boxes are placed by an attendant in a magazine and, in the present embodiment, the boxes in the magazine are fed one by one into convenient position to

35 be assembled with the labels supported on the adhesive-applying members before described. The numeral 70 represents a portion of such magazine and comprises a supporting guide, or track, having side walls,

40 the boxes resting upon an endless belt 71 provided in the bottom of the guide, which belt constantly urges the boxes toward the path of a box-feeding plunger. The guide is slightly inclined downwardly for the

45 more efficient feeding of the boxes therein and is provided with a horizontal portion 72 which extends on the inside of the rotary path of the adhesive-applying members and terminates adjacent the lowermost position

50 of rest of said members opposite the opening 23. The boxes are held in upright position on edge by means of the sides of the guide 70 and one of these sides has an ex-
55 tended portion or pivoted arm 73 which is spring pressed toward the opposite side, this arm and the opposite side of the guide being provided with flanges or stops 74 to limit the advance of the boxes. The foremost box is yieldingly gripped between the

60 fixed side of the guide and the arm 73 and when in this position is directly opposite the opening 23 when the adhesive-applying members are in their lowermost position. And when so gripped the foremost box is

65 also opposite a box-feeding element com-

prising a plunger 75, normally inside of the rotary path of the adhesive-applying members, and supported by an arm 76 having a head 77 mounted for vertical movement in guideways 78 of an upstanding bracket 79, 70 said head having a link 80 connected to an arm 81 of a rock shaft 82 journaled in a bracket 83 on the table. A sleeve 84 is fastened to the rock shaft and is provided with a clutch tooth 85 having an inclined or cam 75 surface, the latter engaged by a conforming slot of a hub 86 loosely journaled on the rock shaft 82 and having an arm 87 to which is pivotally connected a rod 88 extending through a slot in the table 1 and pivoted 80 to a block 89 on a disk 90 journaled in a bracket 91 beneath the table. Block 89 is adjustably mounted in a radial slot 91' in said disk. The disk 90 is moved at proper intervals to rock the shaft 82 in order to 85 effect reciprocation of the plunger 75, such movement being accomplished through the instrumentality of a small pinion 92 connected to the disk 90 and engaged by a segment gear 93 on the cam shaft 9. Portions 90 of the periphery of the gear 92 and segment gear 93 are adapted to interlock in a well known manner in order to lock the plunger in predetermined positions, as when the plunger is at rest during the rotary movement of the adhesive-applying members. The hub 86 is pressed toward the sleeve 84 by means of a spring 94 engaging a head 95 on the shaft 82, and in this manner it will be seen that movement of the plunger is 100 effected through the instrumentality of the clutch tooth 85, and that any substantial or abnormal resistance to the movement of the plunger will result in a longitudinal movement of the hub 86 relative to the sleeve 105 84, and advantage is taken of this movement to throw out the main driving clutch, the same being accomplished by means of a lever 96 fulcrumed on the table connected through a rod 97 to a pawl or dog 98. This latter is adapted to be interposed in the path of a lug 99 on a slidable shaft rod 100 connected to a sleeve 101, through the movement of which latter movement of the main clutch 6 is effected. A spring 102 between the rod 100 and the main frame serves to move said rod 100 in a direction to cause the disengagement of the main clutch and the belt pulley 5, and it will be seen that when the rod 100 has been moved to effect engagement of said clutch and pulley the dog 98 may be placed in the path of the lug or catch 99 to restrain movement of the rod 100 under the influence of the spring 102. Should there be abnormal resistance to the movement of the plunger 75, as by an improper placing of a box or otherwise, the hub 86 will be moved laterally and in turn remove the dog 98 from the path of the catch 99, whereupon the spring 102 will 110 115 120 125 130

effect the disengagement of the main driving mechanism. There might be a tendency for the engaging recess in sleeve 86 to overrun the tooth 85 when the sleeve 86 is rotated in the direction to lift the plunger, and to prevent this the member 84 has a second tooth 85', shown in dotted lines in Fig. 5, this latter tooth having a square face adapted to engage a similar face of a second recess in the sleeve 86, the relative arrangement of the two sets of engaging members being such that the teeth come into engagement with their respective recesses at the same time.

15 The belt 71 is driven by means of a pulley 103 connected by a belt 104 with a pulley 105 on the shaft 9, suitable idler pulleys 106 and 107 being employed to guide the belt 104.

20 The table 1 is provided with a relatively large opening 108 opposite the point where the labels and boxes are assembled. The intermittent rotatory movement of the adhesive applying members is effected by a 25 mutilated pinion 109 fixed to the shaft 20, and driven by a segment gear 110 on the countershaft 13 the pinion 109 comprising four series of teeth, separated by curved concave peripheral faces, and the gear 110 30 having a single series of teeth, the number of teeth of these two elements being so relatively proportioned as to effect a quarter revolution of the shaft 20 and a dwell for each revolution of the gear 110, the curved 35 smooth periphery of the gear 110 co-operating to positively lock the shaft 20 against rotary motion between its intervals of motion.

40 It will be understood that the adhesive supply roller 45 is continuously rotated, and that the roller 46 is in turn rotated thereby when in contact therewith, thereby being coated with adhesive, the rotation of roller 45 being effected through a chain 111, engaging a sprocket wheel 112 on the shaft 9, and another sprocket wheel 113 on a shaft 114, having a gear 115 meshing with a pinion 116 on the roller 45, the pinion 116 45 also meshing with a pinion 117 on a gage roller 118. A suitable clutch may be interposed in this train of gear so as to throw the glue-supply roller into or out of operation, at will.

45 At one side of the opening 108, and beneath the table, is mounted a bracket 119 having a vertically disposed guideway in which reciprocates a combined label-folding and smoothing device, comprising a block 120 carrying two series of brushes 121 and 50 122, the two series being spaced apart so as to permit the boxes and adhering labels to pass therebetween, but the two series being close enough to cause the brushes to wipe the labels on the boxes, press out air bubbles and generally smooth the labels. The upper

part of the block 120 carries two folding, wiping and smoothing rollers 123 and 124 spaced apart in a manner similar to the brushes. These rollers serve to fold and initially wipe the labels on the boxes, and 55 also slightly grip the boxes, but permit their passage on pressure of the plunger 75. When the plunger 75 moves a box against the adhesive provided face of the label on the pads 24, the jointed side of the box first 60 contacts the label, and in order to assist in securing an effective adhesion of the label to the jointed face, the preceding box, which is held in the grip of the rollers 123 and 124, is raised or moved toward the plunger 75, and co-operates with the plunger to press the label against the box in contact with the plunger 75, and immediately thereafter these two boxes move downwardly together 65 under the pressure of the plunger 75. The upward movement of the rollers is effected through the block 120, which is reciprocated at proper times by means of a cam 125, on shaft 9, operated through a lever 126.

70 The labeled boxes are pushed by the plunger 75 through the space between the rollers 123, 124 and between the brushes, and eventually onto a platform 127 in front of a reciprocatory pusher head 128, which is reciprocated by a bell crank lever 129, one 75 arm of which is connected thereto, the other arm being connected to a rod 130 having a slot engaging the cam shaft 9, and a roller adapted to contact with a cam 131 on shaft 9, a spring 132 being connected to move the 80 head 128 into initial pushing position. The jointed faces of the labeled boxes contact the platform 127, and they are pushed one by one along the platform out of alinement with the path of the succeeding boxes and pass 85 beneath a press head 133, which is moved to alternately press down on the boxes and release the same. This head 133 is pivotally jointed to one link 134, of two toggle links, the other link 135 being pivoted to the main 90 frame, and the toggle is operated from shaft 9 by means of a rod 136 slidably engaging said shaft, a cam 137 co-operating with a roller 138 to effect pressing movement of the head 133, a spring 139 being employed to 95 relieve the pressure.

100 As the boxes are moved by the endless belt 71 on the incline to the horizontal portion or support along which they subsequently pass inside of the rotary path of the 105 adhesive-applying members, any box which might assume a position above its fellows is pressed into alinement therewith by a shoe 140, pivoted to a lever 141, the latter being fulcrumed on a pin 142, and pivotally joined 110 to a rod 143, in turn connected to a spring 144 connected to the bracket 79. The shoe 140 is pressed in a direction toward the supply of the oncoming boxes by a plate spring 145 fixed to the lever 141 and in contact with 115

the supporting arm of the shoe, which latter is made in two pivotally connected sections adapted to be adjusted into different relatively fixed positions, so as to set the shoe 5 forward or back. A pin and slot connection 146 serves to limit the pivoted movement of the shoe relative to the lever 141. As the shaft 82 rocks to move a foremost box against a label, the shoe 140 is raised and is 10 pressed outwardly by spring 145. Upon the opposite movement of the shaft 82, the shoe descends and presses any abnormally elevated box into alignment with the other boxes, the pivotal support of the shoe permitting 15 motion of the shoe with the boxes, if required.

While the apparatus forming the subject-matter of the present invention is intended generally for the application of flexible strips to boxes, as for instance a paper or cloth strip to hinge together a base and a cover, the particular embodiment is more especially adapted to efficiently apply such strips when they are in the form of labels. 20 In the latter case the strips are designed either to ornament the box or, as by means of printed matter, to convey information. It is sometimes required that the designs or printed matter shall occupy particular portions of the box, or that the edges of the label strips shall be at predetermined positions on the box, one frequent requirement being that the end edges of the label shall be close to the edges of the box, as for instance, exemplified in the box shown in Fig. 20. The herein described machine accomplishes the above results and others referred to in a most efficient and practical manner, and it will be noted that the arrangement is 30 such as to readily permit the required elements to be adjusted for labeling boxes of different predetermined sizes.

The operation of the machine should be apparent from the foregoing, but may be 45 briefly summarized as follows: Assuming the main clutch to have been thrown to cause the rotation of the main driving shaft, the several elements of the machine will begin to perform their appropriate functions, 50 and an attendant will place boxes in the inclined portion of the guideway 70. These boxes will be conveyed by the belt 71 to the horizontal portion 72 of the guideway and thereafter the boxes fed by the belt will 55 serve to advance boxes along the horizontal guideway toward the plunger. The boxes are placed in the guideway "on edge," the meeting line of the base and cover of one face resting on the horizontal portion of the 60 guideway, and when they arrive at position beneath the plunger a jointed face of the box will be in position to be pressed into contact with a label held by the pads 24 across the opening 23. The plunger 75

moves downwardly in a path parallel to the plane of movement of the adhesive-applying members, and in a line intersecting said path, and presses the endmost box of the magazine 70 through said opening 23, against the label spanning said opening, 65 a preceding box is at the same time lifted against the opposite side of the label so that the label may be relatively firmly pressed against the jointed face of the box when it initially contacts with said label. The plunger moves a sufficient distance downwardly to carry the box outside of the rotary path of the adhesive applying members and thereafter returns to position above the boxes in the box magazine. As the box 70 passes between the rollers 125 and 126 the label which has been stripped from the pads 24 is folded, pressed and wiped against the opposite sides of the box, and the passage of the box between the brushes 121 and 122 75 further wipes and smoothes the label upon the box. The boxes are advanced one by another through the space between the brushes and eventually drop onto the platform 127 on which they are moved laterally, coming 80 beneath the press-head 133 which latter operates to further press the label on the jointed face of the box so as to insure its firm adhesion thereto. Thereafter the boxes move along the platform 127 into convenient position for renewal. By moving the adhesive-applying members in a vertical plane, the plane of said members being normal to the vertical plane, and by disposing the box feeding mechanism on the inside of the rotary path of the adhesive-applying members, a simple, compact and efficient device of the character described is produced, 85 one which takes up but little floor space and one which has great capacity as compared with its relatively small size. It is to be understood that the words vertical, parallel, horizontal, etc., are employed in their relative sense, and that slight deviations therefrom are to be regarded as within the scope of the language employed herein. Virtually the above are accomplished the objects hereinbefore stated.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense. It is also to be understood that the language used in the following claims is intended to cover all of the generic and specific features of the invention herein described, and all statements of the scope of the invention which, as a matter of language, might be said to fall thereunder.

Having described my invention, what I claim as new and desire to secure by Letters Patent is:

1. In an apparatus of the character described, in combination, a plurality of sets of adhesive-applying members mounted to move in a vertical plane, label supply means, box supply means, means adapted to intermittently move said sets in an endless path, 10 means adapted to cause a label from said label supply to adhere to one of said sets of members at a stationary point in said path, means adapted to cause a box from said box supply to contact with an adhering label at another stationary point in said path, and 15 means for moving one member of one of said sets out of contact with the label previous to causing a box to contact with the label adhering to the respective set.
2. In an apparatus of the character described, in combination, a plurality of sets of adhesive-applying members mounted to move in a vertical plane, said members being disposed substantially normally to 20 said plane, label supply means, box supply means, means adapted to intermittently move said sets in an endless path, means adapted to cause a label from said label supply to adhere to one of said sets of members 25 at a stationary point in said path, means adapted to cause a box from said box supply to contact with an adhering label at another stationary point in said path, and means for moving one member of one of said sets out 30 of contact with the label previous to causing a box to contact with the label adhering to the respective set.
3. In an apparatus of the character described, in combination, a plurality of sets 40 of adhesive-applying members mounted to move in a vertical plane, label supply means, box supply means, means adapted to intermittently move said sets in an endless path, means adapted to cause a label from said label supply to adhere to one of said sets of members 45 at a stationary point in said path, means adapted to cause a box from said box supply to contact with an adhering label at another stationary point in said path comprising 50 a plunger adapted to move boxes against labels on said sets in a path parallel to the plane of movement of said sets, and means for moving one member of one of said sets out of contact with the label previous 55 to causing a box to contact with the label adhering to the respective set.
4. In an apparatus of the character described, in combination, a plurality of sets of adhesive-applying members mounted to move in a vertical plane, label supply means, 60 box supply means, means adapted to intermittently move said sets in an endless path, means adapted to cause a label from said label supply to adhere to one of said sets of 65 members at a stationary point in said path, means adapted to move a box from said box supply into contact with an adhering label at another stationary point in said path, comprising a plunger disposed inside of the path of rotation of said sets and adapted to 70 move boxes against labels on said sets in a path parallel to the plane of movement of said sets, and means for moving one member of one of said sets out of contact with the label previous to causing a box to contact with the label adhering to the respective set.
5. In an apparatus of the character described, in combination, a plurality of sets of adhesive-applying members mounted to 75 move in a vertical plane, label supply means, box supply means comprising a magazine, means adapted to intermittently move said sets in an endless path, means adapted to cause a label from said label supply to adhere to one of said sets of members at a stationary point in said path, means adapted to cause a box from said box supply to contact with an adhering label at another stationary point in said path comprising a 80 plunger adapted to move boxes against labels on said sets in a path parallel to the plane of movement of said sets, said magazine extending inside of the path of rotation of said sets to position opposite said plunger, and means for moving one member of one of said sets out of contact with the label previous to causing a box to contact with the label adhering to the respective set.
6. In an apparatus of the character described, in combination, a plurality of sets of adhesive-applying members mounted to move in a vertical plane, label supply means, box supply means comprising a magazine, 85 means adapted to intermittently move said sets in an endless path, means adapted to cause a label from said label supply to adhere to one of said sets of members at a stationary point in said path, means adapted to cause a box from said box supply to contact with an adhering label at another stationary point in said path comprising a 90 plunger adapted to move boxes against labels on said sets in a path parallel to the plane of movement of said sets, said magazine extending inside of the path of rotation of said sets to position opposite said plunger, and means for moving one member of one of said sets out of contact with the label previous to causing a box to contact with the label adhering to the respective set.
7. In an apparatus of the character described, in combination, a plurality of sets of adhesive-applying members mounted to move in a vertical plane, label supply means, 95 means adapted to move a box from said box supply into contact with an adhering label at another stationary point in said path, comprising a plunger disposed inside of the path of rotation of said sets and adapted to move boxes against labels on said sets in a path parallel to the plane of movement of said sets, said magazine extending inside of the path of rotation of said sets to position opposite said plunger, means adapted to constantly urge the boxes in the magazine toward the path of said plunger, and means for moving one 100 member of one of said sets out of contact with the label previous to causing a box to contact with the label adhering to the respective set.
8. In an apparatus of the character described, in combination, a plurality of sets of adhesive-applying members mounted to move in a vertical plane, label supply means, 105 box supply means comprising a magazine, means adapted to intermittently move said sets in an endless path, means adapted to cause a label from said label supply to adhere to one of said sets of members at a stationary point in said path, means adapted to cause a box from said box supply to contact with an adhering label at another stationary point in said path comprising a 110 plunger adapted to move boxes against labels on said sets in a path parallel to the plane of movement of said sets, said magazine extending inside of the path of rotation of said sets to position opposite said plunger, means adapted to constantly urge the boxes in the magazine toward the path of said plunger, and means for moving one 115 member of one of said sets out of contact with the label previous to causing a box to contact with the label adhering to the respective set.
9. In an apparatus of the character described, in combination, a plurality of sets of adhesive-applying members mounted to move in a vertical plane, label supply means, 120 box supply means, means adapted to cause a label from said label supply to adhere to one of said sets of members at a stationary point in said path, means adapted to move a box from said box supply into contact with an adhering label at another stationary point in said path, comprising a plunger disposed inside of the path of rotation of said sets and adapted to move boxes against labels on said sets in a path parallel to the plane of movement of said sets, said magazine extending inside of the path of rotation of said sets to position opposite said plunger, means adapted to constantly urge the boxes in the magazine toward the path of said plunger, and means for moving one 125 member of one of said sets out of contact with the label previous to causing a box to contact with the label adhering to the respective set.

box supply means, means adapted to intermittently move said sets in an endless path, means adapted to cause a label from said label supply to adhere to one of said sets of 5 members at a stationary point in said path, and means adapted to cause a box from said box supply to contact with an adhering label at another stationary point in said path, comprising a plunger, a main driving mechanism, and a driving connection between 10 said main driving mechanism and said plunger adapted to yield upon abnormal resistance to the movement of said plunger.

8. In an apparatus of the character described, in combination, a plurality of sets 15 of adhesive-applying members mounted to move in a vertical plane, label supply means, box supply means, means adapted to intermittently move said sets in an endless path, 20 means adapted to cause a label from said label supply to adhere to one of said sets of members at a stationary point in said path, means adapted to cause a box from said box supply to contact with an adhering label at 25 another stationary point in said path, comprising a reciprocatory plunger, a rock shaft connected to operate said plunger, a main driving shaft and connections between said main driving shaft and said rock shaft to 30 oscillate the latter, comprising clutch elements having spring releasing means, an inclined face on said rock shaft, a movable dog adapted to retain said clutch elements in engagement, and means disposed to be 35 operated by said inclined face and connected to move said dog and thereby permit relative movement of said clutch elements under the influence of said spring means.

9. In an apparatus of the character described, in combination, a plurality of sets 40 of adhesive-applying members mounted to move in a vertical plane, label supply means, box supply means, means adapted to intermittently move said sets in an endless path, 45 means adapted to cause a label from said label supply to adhere to one of said sets of members at a stationary point in said path, means adapted to move a box from said box supply into contact with an adhering label 50 at another stationary point in said path, means for moving one member of one of said sets out of contact with the labels previous to causing a box to contact with the label adhering to the respective set, and 55 means adapted to fold the labels on the boxes.

10. In an apparatus of the character described, in combination, a plurality of sets of adhesive-applying members mounted to 60 move in a vertical plane, said members being disposed substantially normally to said plane, label supply means, box supply means, means adapted to intermittently move said sets in an endless path, means

adapted to cause a label from said label supply to adhere to one of said sets of members at a stationary point in said path, means adapted to move a box from said box supply into contact with an adhering label at another stationary point in said path, means 65 for moving one member of one of said sets out of contact with the labels previous to causing a box to contact with the label adhering to the respective set, and means adapted to fold the opposite ends of the labels on the opposite sides of the boxes. 70

11. In an apparatus of the character described, in combination, a plurality of sets of adhesive-applying members mounted to move in a vertical plane, label supply means, 80 box supply means, means adapted to intermittently move said sets in an endless path, means adapted to cause a label from said label supply to adhere to one of said sets of members at a stationary point in said path, 85 means adapted to move a box from said box supply into contact with an adhering label at another stationary point in the path, comprising a vertically movable plunger adapted to move boxes against labels on said sets in 90 a path parallel to the plane of movement of said sets, means for moving one member of one of said sets out of contact with the labels previous to causing a box to contact with the label adhering to the respective set, 95 and means adapted to fold the labels on the boxes.

12. In an apparatus of the character described, in combination, a plurality of sets of adhesive-applying members mounted to move in a vertical plane, label supply means, box supply means, means adapted to intermittently move said sets in an endless path, 100 means adapted to cause a label from said label supply to adhere to one of said sets of members at a stationary point in said path, means adapted to move a box from said box supply into contact with an adhering label at another stationary point in said path, comprising a plunger adapted to move 105 boxes against labels on said sets in a path parallel to the plane of movement of said sets disposed inside of the path of rotation of said sets, means for moving one member of one of said sets out of contact with the labels previous to causing a box to contact with the label adhering to the respective set, 110 and means adapted to fold the labels on the boxes. 115

13. In an apparatus of the character described, in combination, a plurality of sets of adhesive-applying members mounted to move in a vertical plane, label supply means, box supply means comprising a magazine, means adapted to intermittently move said sets in an endless path, means adapted to cause a label from said label supply to adhere to one of said sets of members at a 120

125

- stationary point in said path, means adapted to move a box from said box supply into contact with an adhering label at another stationary point in said path comprising a 65
 5 plunger adapted to move boxes against labels on said sets in a path parallel to the plane of movement of said sets, said magazine extending inside of the path of rotation of said sets to position opposite said
 10 plunger, means for moving one member of one of said sets out of contact with the labels previous to causing a box to contact with the label adhering to the respective set, and means adapted to fold the labels on the
 15 boxes.
14. In an apparatus of the character described, in combination, a plurality of sets of adhesive-applying members mounted to move in a vertical plane, label supply means, 80
 20 box supply means, means adapted to intermittently move said sets in an endless path, means adapted to cause a label from said label supply to adhere to one of said sets of members at a stationary point in said path, means adapted to cause a box from said box supply to contact with an adhering label at another stationary point in said path, comprising a 85
 25 plunger adapted to move boxes against labels on said sets in a plane parallel to the plane of movement of said sets, said magazine extending inside of the path of rotation of 90
 30 said sets to position opposite said plunger, means for moving one member of one of said sets out of contact with the label previous to causing a box to contact with the label adhering to the respective set, and means adapted to cause a previously labeled box to contact with the opposite face of said adhering label at a time when said first-mentioned box is being assembled in contact therewith. 95
15. In an apparatus of the character described, in combination, a plurality of sets of adhesive-applying members mounted to move in a vertical plane, said members being disposed substantially normally to said plane, label supply means, box supply means, means adapted to intermittently move said 100
 35 sets in an endless path, means adapted to cause a label from said label supply to adhere to one of said sets of members at a stationary point in said path, means adapted to cause a box from said box supply to contact
 40 with one face of an adhering label at another stationary point in said path, and means adapted to cause a previously labeled box to contact with the opposite face of said adhering label at a time when said first-mentioned
 45 box is being assembled in contact therewith. 105
 50
16. In an apparatus of the character described, in combination, a plurality of sets of adhesive-applying members mounted to move in a vertical plane, label supply means, 110
 55 box supply means, means adapted to intermittently move said sets in an endless path, means adapted to cause a label from said label supply to adhere to one of said sets of members at a stationary point in said path,
 60 means adapted to cause a box from said box supply to contact with an adhering label at another stationary point in said path, comprising a plunger adapted to move boxes against labels on said sets in a plane parallel 115
 to the plane of movement of said sets, means 65
 for moving one member of one of said sets out of contact with the label previous to causing a box to contact with the label adhering to the respective set, and means adapted to cause a previously labeled box to 70
 75 contact with the opposite face of said adhering label at a time when said first-mentioned box is being assembled in contact therewith.
17. In an apparatus of the character described, in combination, a plurality of sets of adhesive-applying members mounted to move in a vertical plane, label supply means, box supply means, comprising a magazine, means adapted to intermittently move said sets in an endless path, means adapted to cause a label from said label supply to adhere to one of said sets of members at a stationary point in said path, means adapted to cause a box from said box supply to contact with an adhering label at another stationary point in said path, comprising a 80
 85 plunger adapted to move boxes against labels on said sets in a plane parallel to the plane of movement of said sets, said magazine extending inside of the path of rotation of 90
 90 said sets to position opposite said plunger, means for moving one member of one of said sets out of contact with the label previous to causing a box to contact with the label adhering to the respective set, and means adapted to cause a previously labeled box to contact with the opposite face of said adhering label at a time when said first-mentioned box is being assembled in contact therewith. 95
18. In an apparatus of the character described, in combination, a plurality of sets of adhesive-applying members mounted to move in a vertical plane, label supply means, box supply means, means adapted to intermittently move said sets in an endless path, means adapted to cause a label from said label supply to adhere to one of said sets of members at a stationary point in said path, and means adapted to cause a box from said box supply to contact with one face of an adhering label at another stationary point in said path, comprising a plunger, and a folder adapted to yieldingly grip the labeled box and move the same against a succeeding 110
 115 label.
19. In an apparatus of the character described, in combination, a plurality of sets of adhesive-applying members mounted to move in a vertical plane, label supply means, 120
 125 box supply means, means adapted to intermittently move said sets in an endless path, means adapted to cause a label from said label supply to adhere to one of said sets of members at a stationary point in said path, means adapted to cause a box from said box supply to contact with an adhering label at another stationary point in said path, means

- for moving one member of one of said sets out of contact with the labels previous to causing a box to contact with the label adhering to the respective set, and means 65
 5 adapted to fold the labels on the boxes comprising a roller adapted to wipe the label on a face of each box adjacent the initially contacting face, and a brush adapted to smooth said labels on said adjacent face. 70
- 10 20. In an apparatus of the character described, in combination, a plurality of sets of adhesive-applying members mounted to move in a vertical plane, label supply means, box supply means, means adapted to intermittently move said sets in an endless path, means adapted to cause a label from said label supply to adhere to one of said sets of members at a stationary point in said path, means adapted to cause a box from said box 75
 15 supply to contact with an adhering label at another stationary point in said path, means for moving one member of one of said sets out of contact with the labels previous to causing a box to contact with the label adhering to the respective set, means adapted to fold the labels on the boxes, and means adapted to move a labeled box out of alignment with the path of the boxes to be labeled. 80
- 20 25. In an apparatus of the character described, in combination, a plurality of sets of adhesive-applying members mounted to move in a vertical plane, label supply means, box supply means, means adapted to intermittently move said sets in an endless path, means adapted to cause a label from said label supply to adhere to one of said sets of members at a stationary point in said path, means adapted to cause a box from said box supply to contact with one face of an adhering label at another stationary point in said path, means adapted to cause a previously labeled box to be moved into contact with the opposite face of said adhering label at a time when said first-mentioned box is in contact therewith, means adapted to fold the labels on the boxes, and means adapted to move the labeled boxes out of alignment with the path of the boxes to be labeled. 85
 30 35
- 40 45. In an apparatus of the character described, in combination, a plurality of sets of adhesive-applying members mounted to move in a vertical plane, label supply means, box supply means, means adapted to intermittently move said sets in an endless path, means adapted to cause a label from said label supply to adhere to one of said sets of members at a stationary point in said path, and means adapted to cause a box from said box supply to contact with an adhering label at another stationary point in said path. 90
 40 45
- 50 55. In an apparatus of the character described, in combination, a plurality of sets of adhesive-applying members mounted to move in a vertical plane, label supply means, box supply means, means adapted to intermittently move said sets in an endless path, means adapted to cause a label from said label supply to adhere to one of said sets of members at a stationary point in said path, and means adapted to cause a box from said box supply to contact with an adhering label at another stationary point in said path. 95
 50 55
- 60 65. In an apparatus of the character described, in combination, a plurality of sets of adhesive-applying members mounted to rotate in a vertical plane, label supply means, box supply means, means adapted to intermittently move said sets in an endless path, a roller adapted to apply adhesive to said members, means adapted to move said roller and cause the same to exert a uniform pressure against all parts of said members in applying adhesive to the latter, means adapted to cause a label from said label supply to adhere to one of said sets of members at a stationary point in said path, and means adapted to cause a box from said box supply to contact with an adhering label at another stationary point in said path. 100
 60 65
- 70 75. In an apparatus of the character described, in combination, a plurality of sets of adhesive-applying members mounted to rotate in a vertical plane, said members being disposed substantially normally to said plane, label supply means, box supply means, means adapted to intermittently move said sets in an endless path, a roller adapted to apply adhesive to said members, means adapted to move said roller and cause the same to exert a uniform pressure against all parts of said members in applying adhesive to the latter, means adapted to cause a label from said label supply to adhere to one of said sets of members at a stationary point in said path, and means adapted to 105
 70 75
- 80 85. In an apparatus of the character described, in combination, a plurality of sets of adhesive-applying members mounted to rotate in a vertical plane, said members being disposed substantially normally to said plane, label supply means, box supply means, means adapted to intermittently move said sets in an endless path, a roller adapted to apply adhesive to said members, means adapted to move said roller and cause the same to exert a uniform pressure against all parts of said members in applying adhesive to the latter, means adapted to cause a label from said label supply to adhere to one of said sets of members at a stationary point in said path, and means adapted to 110
 80 85
- 90 95. In an apparatus of the character described, in combination, a plurality of sets of adhesive-applying members mounted to rotate in a vertical plane, said members being disposed substantially normally to said plane, label supply means, box supply means, means adapted to intermittently move said sets in an endless path, a roller adapted to apply adhesive to said members, means adapted to move said roller and cause the same to exert a uniform pressure against all parts of said members in applying adhesive to the latter, means adapted to cause a label from said label supply to adhere to one of said sets of members at a stationary point in said path, and means adapted to 115
 90 95
- 100 105. In an apparatus of the character described, in combination, a plurality of sets of adhesive-applying members mounted to rotate in a vertical plane, said members being disposed substantially normally to said plane, label supply means, box supply means, means adapted to intermittently move said sets in an endless path, a roller adapted to apply adhesive to said members, means adapted to move said roller and cause the same to exert a uniform pressure against all parts of said members in applying adhesive to the latter, means adapted to cause a label from said label supply to adhere to one of said sets of members at a stationary point in said path, and means adapted to 120
 100 105
- 110 115. In an apparatus of the character described, in combination, a plurality of sets of adhesive-applying members mounted to rotate in a vertical plane, said members being disposed substantially normally to said plane, label supply means, box supply means, means adapted to intermittently move said sets in an endless path, a roller adapted to apply adhesive to said members, means adapted to move said roller and cause the same to exert a uniform pressure against all parts of said members in applying adhesive to the latter, means adapted to cause a label from said label supply to adhere to one of said sets of members at a stationary point in said path, and means adapted to 125
 110 115

cause a box from said box supply to contact with an adhering label at another stationary point in said path.

26. In an apparatus of the character described, in combination, a plurality of sets of adhesive-applying members mounted to rotate in a vertical plane, said members being disposed substantially normally to said plane, label supply means, box supply means, means adapted to intermittently move said sets in an endless path, an adhesive supply, an adhesive-applying roller movable from said adhesive supply to the adhesive-applying member in position, means adapted to yieldingly move said roller toward said member in position, cam means adapted to produce a uniform pressure of said roller on the face of said member in position, means adapted to cause a label from said label supply to adhere to one of said sets of members at a stationary point in said path, and means adapted to cause a box from said box supply to contact with an adhering label at another stationary point in said path.

27. In an apparatus of the character described, in combination, a plurality of sets of adhesive-applying members mounted to move in a vertical plane, said members being disposed substantially normally to said plane, box supply means, means adapted to intermittently move said sets in an endless path, means adapted to cause a label to adhere to one of said sets of members at a stationary point in said path, comprising a label magazine having means to removably support the labels with the bottom label adjacent the path of the adhesive-applying members, means adapted to move said magazine toward and from the adhesive-applying members and cause the bottom label to adhere to said members, means adapted to cause a box from said box supply to contact with an adhering label at another stationary point in said path, and means for moving one member of one of said sets out of contact with the labels previous to causing a box to contact with the label adhering to the respective set.

28. In an apparatus of the character described, in combination, a carrier comprising a horizontal rotatable shaft, a plurality of sets of adhesive-applying plates parallel to said shaft and mounted on said carrier to rotate therewith, a plate of each set being movable into and out of adhesive-applying position relative to another plate of the same set, means adapted to intermittently rotate said shaft, an adhesive-applying roller and a label magazine disposed outside the rotary path of said plates adjacent different points of rest in said path, and adapted to move toward and from said path, and an article feeding plunger disposed adjacent

another point of rest in said path inside of said path, and adapted to move in a line intersecting said rotary path.

29. In an apparatus of the character described, in combination, a carrier comprising a horizontal rotatable shaft, a plurality of sets of adhesive-applying plates parallel to said shaft and mounted on said carrier to rotate therewith, a plate of each set being pivoted on said carrier to move into and out of adhesive-applying position relative to another plate, a gear on each pivot, levers comprising teeth engaging said gears, rods guided on said carrier and connected to said levers, a reciprocatory pawl adapted to move said rods, means adapted to intermittently rotate said shaft, an adhesive-applying roller and a label magazine disposed outside the rotary path of said plates adjacent different points of rest in said path and adapted to move toward and from said path, and an article feeding plunger disposed adjacent another point of rest in said path inside of said path and adapted to move in a line intersecting said rotary path.

30. In an apparatus of the character described, in combination, a carrier comprising a horizontal rotatable shaft, a plurality of sets of adhesive-applying plates parallel to said shaft and mounted on said carrier to rotate therewith, a plate of each set being pivoted on said carrier to move into and out of adhesive-applying position relative to another plate, a gear on each pivot, levers comprising teeth engaging said gears, rods guided on said carrier and connected to said levers, and each having an anti-friction roller, a cam concentric with said shaft, a pawl adapted to engage said rollers, means adapted to positively move said pawl to engage said rollers and cause the latter to engage said cam, means adapted to intermittently rotate said shaft, an adhesive-applying roller and a label magazine disposed outside the rotary path of said plates adjacent different points of rest in said path and adapted to move toward and from said path, and an article feeding plunger disposed adjacent another point of rest in said path inside of said path and adapted to move in a line intersecting said rotary path.

31. In an apparatus of the character described, in combination, a carrier comprising a horizontal rotatable shaft, a plurality of sets of adhesive-applying plates parallel to said shaft and mounted on said carrier to rotate therewith, a plate of each set being movable into and out of adhesive-applying position relative to another plate of the same set, means adapted to intermittently rotate said shaft, an adhesive-applying roller and a label magazine disposed outside the rotary path of said plates adjacent different points of rest in said path and

- adapted to move toward and from said path, an article feeding plunger disposed adjacent another point of rest in said path inside of said path, and adapted to move in a line 5 intersecting said rotary path, means adapted to move said roller comprising a spring to move the roller toward said path, a cam, and connections between said cam and roller, whereby the pressure of said roller on said 10 plates is rendered uniform by said cam.
32. In an apparatus of the character described, in combination, a table, a horizontal rotatable shaft supported thereby, a carrier rotatable with said shaft, a plurality of sets 15 of adhesive applying plates parallel to said shaft mounted on said carrier to rotate therewith, a plate of each set being movable into and out of adhesive applying position relative to another, means adapted to intermittently rotate said shaft, an adhesive 20 applying roller and a label magazine disposed outside the rotary path of said plates adjacent different points of rest of said path, and adapted to move toward and from said 25 path, an article feeding plunger disposed adjacent another point of rest of said path inside of said path and movable in a line intersecting said path, a presser movable toward and from said rotary path at another 30 point of rest in said path, a cam shaft, and means comprising a series of cams on said cam shaft adapted to effect the movements of said magazine, roller and presser at proper times.
- 35 33. In an apparatus of the character described, in combination, a plurality of sets of adhesive applying members mounted to move in a predetermined plane, said members being disposed substantially normally to said plane, label supply means, box supply means, means adapted to intermittently move said sets in an endless path, means adapted to cause a label from said label supply to adhere to one of said sets of members at a stationary point in said path, and means 40 adapted to move a box from said box supply into contact with an adhering label at another stationary point in said path comprising a reciprocatory member normally disposed inside the path of said sets and adapted to move the boxes in a plane transversely of said members.
34. In an apparatus of the character described, in combination, a plurality of sets of adhesive applying members mounted to 45 move to a predetermined plane, said members being disposed substantially normally to said plane, label supply means, box supply means, means adapted to intermittently move said sets in an endless path, means adapted to cause a label from said label supply to adhere to one of said sets of members at a stationary point in said path, and means adapted to move a box from said box supply 50 into contact with an adhering label at another stationary point in said path comprising a reciprocatory member normally disposed inside the path of said sets and adapted to move the boxes in a plane transversely of said members.
- 35 35. In an apparatus of the character described, in combination, a plurality of sets of adhesive applying members mounted to move in a predetermined plane, said members being disposed substantially normally to said plane, label supply means, box supply means, means adapted to intermittently move said sets in an endless path, means adapted to cause a label from said label supply to adhere to one of said sets of members at a stationary point in said path, and means adapted to move a box from said box supply 55 into contact with an adhering label at another stationary point in said path comprising a reciprocatory member normally disposed inside the path of said sets and adapted to move the boxes in a plane transversely of said members and parallel to said path.
- In testimony whereof I affix my signature, in the presence of two witnesses.
- HAROLD CARLE.
